DRAW CATCH FOR LUGGAGE OR THE LIKE

Edward M. Stolarz, Yorktown Heights, N.Y., assignor to Presto Lock Co., Inc., Garfield, N.J.

Filed Sept. 14, 1971, Ser. No. 180,534

Term of patent 14 years

Int. Cl. D8—07

U.S. Cl. D8—129

FIG. 1

FIG. 2

FIG. 3

FIG. 4

FIG. 5

FIG. 1 is a top plan view of a draw catch for luggage or the like embodying my new design;

FIG. 2 is an end view as seen from the right of FIG. 1, the view from the opposite side being the same;

FIG. 3 is a side elevational view as seen from the top of FIG. 1;

FIG. 4 is a side elevational view as seen from the bottom of FIG. 5; and

FIG. 5 is a bottom plan view.

I claim:

The ornamental design for a draw catch for luggage or the like, as shown and described.
